CAN OPENING RECEPTACLE HANDLE

Ronald A. Wendlandt, Cincinnati, Ohio, assignor to The Heekin Can Company, Cincinnati, Ohio, a corporation of Ohio

Application May 5, 1958, Serial No. 732,898

4 Claims. (Cl. 30—10)

This invention pertains to tools for opening sealed food and refreshment containers and more particularly to a hand operated tool of the class described that is primarily intended to be mounted on a portable receptacle to serve as a drop handle for lifting and carrying the receptacle.

It is the principal object of the invention to provide a device of the type indicated having a tin can puncturing blade which is at all times protected against accidental damage and is likewise guarded so that users of the portable receptacle will not be injured by unintentional contact with the blade.

Another object of the invention is to provide a rugged, durable, ornamental, and convenient tool for opening sealed food and refreshment containers which is capable of being mounted on a portable receptacle and utilized to lift and carry said receptacle from place to place.

Further objects of the invention are to provide a novel and simplified device for maintaining a tin can in puncturing position with respect to the handle operated blade; to provide a one-piece receptacle mounted bracket that has a single moving part in the form of a blade carrying, ring-shaped handle; and to provide an improved hand manipulated tool which has lateral projections adjacent the blade that engage the can bead to support the can in opening position for operation by the puncturing blade.

To the accomplishment of the above and related objects my invention is preferably embodied in the form illustrated in the accompanying drawing, attention being called to the fact that the drawing and description are illustrative only and that changes may be made in the specific construction illustrated and described, so long as the scope of the appended claims is not violated.

In the drawing wherein like reference numerals indicate similar parts throughout the several views:

Fig. 1 is a side elevational view of a portable receptacle, represented as a picnic cooler, showing one of the handles thereof in position to puncture the end wall of the conventional tin can for packaging foods and refreshments, or the like.

Fig. 2 is an enlarged, fragmental, perspective view of one of the opener-handles as it might appear when removed from the portable receptacle shown in Fig. 1.

Fig. 3 is a section taken on line 3—3 of Fig. 2 illustrating the opener-handle mounted on the side wall of the portable receptacle shown in Fig. 1.

Fig. 4 is a sectional view similar to that shown in Fig. 3 illustrating the opener-handle in operative position with respect to a tin can to be opened thereby.

Fig. 5 is a fragmental, sectional view taken on line 5—5 of Fig. 2 showing the opener-handle attached to the side wall of the portable receptacle shown in Fig. 1.

Referring more particularly to the drawing, it will be seen that my can opening receptacle handle, generally indicated by the reference numeral 8, is illustrated as applied to a portable receptacle such as a picnic cooler 9 that has an upstanding side wall 10, a bottom 11, and a top closure 12. The picnic cooler is of the usual type and consists of spaced external and internal containers

2

both made of metal and having a heat insulating material filling the space between the two containers.

As illustrated in Fig. 1 a pair of my handles 8 are mounted in opposed relationship on the side wall 10 of the portable receptacle and, as best shown in Fig. 2, each handle comprises a bracket 13 that has a one-piece body formed with a receptacle mounting base 14. The base is substantially rectangular in plan and is suitably provided at its corners with holes 15 through which are passed rivets that secure the base to the receptacle side wall 10. This base also has a central hole 16 formed therethrough and is provided with a laterally elongated, downwardly opening hood shaped portion 17 projecting from the upper portion of the base and surrounding the said hole 16. A pair of laterally spaced walls 18 and 19 extend outwardly at right angles to the base and close the opposite ends of the hood shaped portion, said walls each having a bearing hole 20 formed therethrough in positions to be in axial alignment with each other.

20 A ring-shaped drop handle 21 is swingable mounted on the bracket 8 and, as best shown in Fig. 2, is substantially rectangular in configuration to provide a straight portion 22, and parallel extensions 23 and 24 connected to the ends of the straight portion which at their ends are connected to a hand hold portion 24 disposed parallel to the straight portion 22. The straight portion 22 extends laterally between the side walls 18 and 19 of the bracket and has its end portions journaled in the bearing holes 20 formed in the side walls 18 and 19. The straight portion 25 is precluded from axial displacement in said bearing holes of the side walls by means of shoulders or other abutments 25 projecting from the projecting ends of the straight portion 22.

25 30 A V-shaped blade 26 is mounted on the central part of the straight portion 22 of the handle by forming a slot 27 in the straight portion and driving the blade into the slot so that the broad end is affixed to the handle whilst the major part of the blade carrying a sharp point projects radially from the said straight portion.

35 40 The downwardly facing opening in the hood 17 has a very irregular configuration, said opening being indicated by the reference numeral 28 in Fig. 2. The configuration of the downwardly facing opening may include a pair of depending fingers 29 and 30 spaced on opposite sides of the center of the hood and forming between them a semi-circular seat 31 which, as shown in Fig. 3, preferably to receive the upper edge portion of the usual crown type bottle cap 32 that is illustrated in dotted lines in said figure. The lower edge of the base around the hole 16 45 is notched at 32, said notch being V-shaped in plan and opening out into said hole 16 in the base. This notch freely receives and houses the V-shaped blade 26 when the drop handle is in its inoperative suspended position on the bracket 14.

50 55 A pair of laterally spaced, can bead gripping abutments 33 and 34 project outwardly from the base and are positioned on opposite sides of the notch 32 formed therein. It will, therefore, be seen that I have provided a drop

55 60 handle 21 that may be swingably mounted on a bracket 8 suitably fastened to the side wall 10 of a portable receptacle, or the like. When it is desired to lift and carry the receptacle it is only necessary to grasp the straight portion 24 of the handle rotate it upwardly through 180° so that the handle extends above the top 65 of the receptacle and then lift said receptacle with the handle. In the event it is desired to open a refreshment container such as a bottle having the usual crown type cap, the capped bottle is placed in the position shown in dotted lines in Fig. 3 of the drawings wherein the

70 upper part of the edge of the bottle cap will be held between the fingers 29 and 30 within the notch 31 formed in the hood 17 whilst the opposite side of the crown cap

will bear against the can gripping abutments 33 and 34 on the base. By placing downward pressure on the bottom portion of the bottle, the crown cap so held by the bracket will be detached from the bottle so that its contents may be consumed.

In the event a tin can containing food or refreshments is required to be opened it is only necessary to rotate the handle 21 upwardly into a position approximating that shown in full lines in Fig. 4, inserting a can underneath the hood such that the top bead thereof will rest upon the gripping abutments 33 and 34 of the base and then by forcing the handle downwardly the blade 26 will enter the top end wall of the can and puncture a hole therein for removal of the contents of the can.

Having thus described my invention and the objects attained thereby, what I claim is:

1. A device of the character described comprising a bracket for attachment to the side wall of a portable receptacle, said bracket having a one-piece body formed with a mounting base having a central hole formed therethrough, a laterally elongated, downwardly opening hood shaped portion projecting from the base, a pair of laterally spaced walls extending at right angles from the base and closing the opposite ends of the hood shaped portion, said end walls each having a bearing hole formed therethrough in axial alignment with each other, a ring-shaped handle having a straight portion extending laterally between the end walls of the bracket and having its end portions journalled in the bearing holes, a V-shaped blade mounted on the central part of the straight portion and adapted to lie within the confines of the hole in the base when the handle is in inoperative, suspended position, said blade being confined in the bracket within the hood when the handle is in its upper lift position, and a pair of laterally spaced, can bead gripping abutments within the hood and projecting outwardly from the base on opposite sides of the blade and beneath the straight portion of the handle.

2. A device of the character described comprising a bracket for attachment to the upper part of the side wall of a portable receptacle, said bracket having a one-piece body formed with a mounting base, a laterally elongated, downwardly opening hood shaped portion projecting from the base, a pair of laterally spaced walls extending at right angles from the base and closing opposed ends of the hood shaped portion, said end walls each having a bearing hole formed therethrough in axial alignment with each other, a ring-shaped handle having a straight portion extending laterally between the end walls of the bracket and having its end portions journalled in the bearing holes, said handle having swinging movement in the bearing holes between an inoperative de-

pend position beside the receptacle wall to an upstanding receptacle lifting position, a V-shaped blade mounted on the central part of and projecting outwardly from the straight portion of the handle and swingable by the handle entirely within the hood, and a pair of laterally spaced can bead gripping abutments on the base and positioned within the hood and projecting outwardly from the base on opposite sides of the blade and beneath the straight portion of the handle.

3. As an article of manufacture a bracket having a hollow, mounting base, a laterally elongated, downwardly opening hood shaped portion projecting from the base, a pair of laterally spaced walls extending at right angles from the base and closing opposed ends of the hood shaped portion, said end walls each having a bearing hole formed therethrough in axial alignment with each other, a ring-shaped handle having a straight portion disposed within the hood shaped portion and extending laterally between the end walls of the bracket, said straight portion having its ends journalled in the bearing holes, said handle having swinging movement in the bearing holes between an inoperative depending position to an upstanding position, a V-shaped blade mounted on the central part of and projecting outwardly from the straight portion of the handle and swingable by the handle entirely within the hood, and a pair of laterally spaced abutments on the base positioned within the hood beneath the straight portion of the handle and projecting outwardly from the base on opposite sides of the blade.

4. As an article of manufacture a hollow mounting base, a pair of laterally spaced apart ears extending at right angles from the base, a downwardly opening hood portion projecting from the base, a ring shaped handle having a straight portion journalled at its ends in the ears on the base, a V-shaped can puncturing blade mounted on the central part of and projecting outwardly from the straight portion of the handle and swingable by the handle entirely within the hood, and a pair of laterally spaced can bead gripping abutments on the base, positioned within the hood beneath the straight portion of the handle and projecting outwardly from the base on opposite sides of the blade.
